UNITED STATES PATENT OFFICE.

HERMAN TUGENDER, OF NEW YORK, N. Y.

PLATE-HOLDING MEANS FOR PRINTING-MACHINES.

1,079,076.

Specification of Letters Patent. Patented Nov. 18, 1913.

Application filed November 22, 1911. Serial No. 661,768.

To all whom it may concern:

Be it known that I, HERMAN TUGENDER, a citizen of the United States, residing in the borough of Bronx, city, county, and State of New York, have invented a new and useful Improvement in Plate-Holding Means for Printing-Machines, of which the following is a description.

This invention relates to clamps or holders for stereotype and other similar plates, and has particular reference to means by which plates of the character noted can be properly lined up and securely clamped on the plate-block.

Among the objects of my invention may be noted the following: to provide a clamp or holder of the character stated which can be quickly set in place and clamped in position against the margin of the plate so as to hold the latter firmly and in proper alignment; to provide a plate-holding clamp with means by which it can be made to clean the track in which it operates; to provide a plate-holding clamp with means for limiting the movement of the base thereof in two directions so that the clamp may be readily removed from the block when the base has reached the proper position, and so that the operative position of the clamp in the block may be instantly secured; to provide a plate-clamp or holder with means whereby it may engage the periphery and bottom of the plate so as to obtain upon the latter a firm clamping grip and also be held firmly in the block against displacement; to provide a clamp for holding plates, which can be lifted from the block immediately upon its release from the plate and without the necessity of having to slide the same along the groove of the block until the open end thereof is reached; to provide a structure of block in combination with a clamp whereby the latter is firmly held in position against displacement; to provide a block of a form to afford a support for the plate at and near the corners thereof; to provide a plate-clamp with means for coöperation with a plate-shifter; to provide a plate-holder with means for supporting the corners of the plate; and to provide certain details of construction by which the foregoing objects are secured and which make of the clamp a cheap, simple and effective instrument for the purpose.

With the above objects in view, and others which will be detailed during the course of this description, my invention consists in the

parts, features, elements and combinations of elements, all as hereafter described and claimed.

In order that my invention may be clearly understood, I have provided drawings wherein:

Figure 1 is a top-plan view of a section of a block, showing a plurality of plates held in position by clamps or holders made according to my invention; Fig. 2 is a transverse section taken on the line 2—2 of Fig. 1; Fig. 3 is a perspective of my improved clamp; Fig. 4 is a section of a block and of a plate thereon, showing my clamp in an unclamped position; Fig. 5 is a view similar to Fig. 1, showing my clamp in a clamped position; Fig. 6 is a top-plan of Fig. 5; Fig. 7 is a longitudinal section of my clamp, the screw being shown in elevation; Fig. 8 is a bottom-plan of the top-piece, the screw being shown in section; Fig. 9 is an elevation showing another form of my invention, wherein the lug is made separate from the top-piece; and Fig. 10 is an elevation showing still another form of my invention, wherein the top-piece has a plurality of lugs and base-pieces coöperating therewith.

Upon reference to the drawings, Figs. 3 to 8, it will be seen that my clamp or holder consists of two principal parts, viz., a base-piece and a holding-screw. The base-piece 1 is oblong in form and has a screw-threaded aperture 2, formed therein, and also has, as a part thereof, a vertically-extending pin 3, near one end and at one longitudinal margin thereof. The top-piece 4 may be slightly longer than the base-piece and is rectangular in form, but particularly has its longitudinal edges beveled, as at 5, so as to converge from top to bottom. Either one or both of the edges may be beveled. The degree of the angle or bevel of the sides is important only in its aspect of corresponding approximately with the bevel of the periphery, or edges, of the plate. On the bottom of the top-piece is preferably rigidly secured a lug 6, made substantially in the form of a square, with two opposite angles slabbed off slightly and leaving oppositely-extending lips 7, projecting a slight distance beyond the bases of the beveled sides of the top-piece. The lug 6 is located on the bottom of the top-piece substantially centrally thereof and with the other opposite angles 8 arranged so as to be in the longitudinal center

of the bottom of said top-piece. The top-piece and its lug are bored centrally at 9, and the top surface of the top-piece is provided with a countersink or depression 10, surrounding said bore, the latter being considerably larger than the bore in the top-piece. The screw 11, in diameter smaller than the bore in the top-piece and lug, passes through the latter, and the head 12 thereof co-operates with the countersink surrounding said bore. The screw threads into the bore of the base-piece and is provided on its end with an integral head 13^a and washer 13, which co-operates with the bottom surface of the base-piece. The head or washer may be threaded on and riveted to said screw. The screw is of a length sufficient only, when its head is in the countersink of the top-piece and its fixed washer is snug against the bottom surface of the base-piece, to enable the base-piece to clear the bottom surface of the overhanging flanges 14, which, together with the side-walls 15, and bottom surface 16, produce the diagonal grooves of the block 17, in which the clamp operates; and when the clamp is set in the block the bottom surface of the top-piece is at rest upon the top surfaces of said overhanging flanges. The adjacent edges 18 of the overhanging flanges are beveled or inclined, or made to converge from the top to the bottom surfaces thereof to any desired degree; but, whatever the degree of their angle, they should correspond substantially with the degree of bevel given to the four sides 19, of the lug. The importance of the co-operating bevels of the lug 6, and flanges 18, is that, together, they have a wedging action, when the screw 11 is tightened, which gives them a very firm grip or hold upon each other and prevents the clamps from shifting after securing the plates in position preparatory to printing.

It will now be understood that the screw can be turned, for example, counter-clockwise to bring the washer 13 thereof into firm engagement with the bottom surface of the base-piece, see Fig. 4, thus locking the screw and base-piece so as to be turned together. This is important since, when the clamp is in the block, a slight turn of the screw, to secure its rigid relation to the base-piece, will enable the screw thereafter to turn the base-piece into locking position in the holder, see Fig. 5, and, in so doing, to clear or clean a way for itself, in the event the grooves in the holder be choked, or clotted from any cause, or if the bottom surfaces of the overhanging flanges are in such condition. This, as a preliminary to locking the clamp upon the block and plate, is necessarily an important feature of my invention. Moreover, this relation of the screw and the base-piece enables the former to instantly turn the latter into both the oper-

ative and inoperative position of the base-piece so that, on the one hand, the clamp can be quickly set against the plate to secure the latter to the block and, on the other hand, the clamp can be quickly removed from the block when desired. These actions are obtained also by reason of the pin or stop 3, carried on the upper surface of the base-piece, and which co-operates with the adjacent walls of the overhanging flanges 14, of the block. The particular form given to the lug 6, on the bottom of the top-piece, enables it to readily engage and co-operate with the beveled flanges of the block irrespective of how the clamp is set within the block. This feature is important since the top-piece of the clamp may be set at varying angles in the block, which thus adapts the clamp to both right and left-hand work. The lips 7, of the lug 6, are slightly recessed in their upper surfaces at 20, to enable them to slide under the plate 21, and, in co-operation with the top-piece, embrace said plate.

Having entered the base-piece of the clamp into the groove 16 of the block, between the beveled walls of the flanges 14, the operator first turns the screw back slightly to lock the base-piece and the washer firmly together, which is accomplished by the pin 3, on the base-piece, engaging one of the beveled flanges of the block. The operator then turns the screw in the opposite direction, which drives the base-piece around to clamping position, which operation will clear or clean a path for the base piece and enable it to be clamped tightly against the bottom of the flanges of the block, the pin coming into engagement with the opposite beveled flange, thus limiting the movement of the base-piece in that direction. This enables the two parts of the clamp to be drawn tightly together against the opposite surfaces of the opposed flanges of the block upon further turning the screw in a clockwise direction. When the clamp is properly engaged with the plate, the lip 7, on one side of the lug, will firmly grip against the bottom of the plate and the beveled edge 6 of the top-piece of that side will firmly grip the beveled edge of the plate. In this condition of the parts, the top-piece and base-piece will be firmly clamped against the flanges of the block.

As shown in Figs. 1, 2, 6 and 8, notches 25 may be provided in the longitudinal edge or edges of the top-piece, which are adapted for co-operation with a plate-shifter of my invention, but which need not be herein set forth. It is sufficient to note that the notched side of the piece will be placed adjacent the plate and the shifter will enter the notches and engage the plate to force the latter into proper position. In this connection, the wedge shape of the lug 6 will be appreciated since, when the plate-shifter is 130

used, a great strain is brought upon the plate and clamps, and the tight grip between the clamps and block prevents the clamps from shifting while the plate is being moved to the desired register.

In the form of Fig. 9, the lug 6 is made independent of the top-piece and the latter is provided with a countersink 22, in the bottom surface, while the lug is provided with a vertical projection 23, for coöperation with said countersink. Thus, the clamp is formed in four parts instead of in three. By this construction, the top-piece, when in the block, may swivel upon the lug 6 and be made to assume any angle necessary for it to properly coöperate with the plate, regardless of the form of the latter or its position on the block.

In the form of Fig. 10, a long bar 24 takes the place of the top-piece, the bottom surface of which has applied thereto a plurality of lugs 6, the other complementary clamping parts being the same as in the other forms of my invention.

It frequently happens that one or more of the corners of the plate will extend over the edge of a flange 14 of the ordinary block and hang above a groove in said block without any support. This necessitates the provision of independent means in the groove for supporting said corners to prevent them from becoming bent or otherwise injured. In very great measure, this objection and fault is remedied by the structure of my block, viz., by providing the overhanging flanges 14, which reduce the size of the top of the slots in the block and afford a very material support for the corners of the plate. However, to avoid any possibility of bending or breaking the corners of the plates, under the conditions noted, I may make the lug 6 sufficiently extensive to project beyond the top-piece and well into the groove of the block so as to provide a corner support for the plate, as shown at 26, in Fig. 1. This is a very effective means for the purpose, since the lug wedges tightly in the slot between the opposed beveled edges 18 of the flanges and has its top surface lying flush with the top surfaces of said flanges.

In the drawings, I have shown only a flat plate and flat supporting-block; but, I desire it understood that my invention is equally applicable to curved or cylindrical blocks and that the clamps are just as effective on any form of surface to which a printing-plate can be adapted.

Having thus described my invention, what I claim and desire to secure by Letters Patent is:

1. A plate-holder comprising an elongated base-piece, an elongated top-piece, and means for holding the two pieces in coöperative relation, the base-piece being provided with means projecting from its top

surface for limiting its movements in opposite directions.

2. A plate-holder comprising a base-piece, a top-piece, and means for holding the two pieces in coöperative relation, the base-piece having a pin on its top surface for limiting the movement of said piece in opposite directions.

3. In combination with a block having a groove with over-hanging flanges, a plate-holder having a base-piece of a form to turn freely in the groove of the block beneath the said flanges, said base-piece having means on its top surface for coöperation with the flanges of the block for limiting the movement of the base-piece in the groove in opposite circular directions.

4. A plate-holder comprising a base-piece, a top-piece, and means for holding the two pieces in coöperative relation, and means carried by the holding means for frictionally engaging the bottom surface of the base-piece for holding the two rigidly together so that one may turn the other in opposite circular directions, and means for limiting said movement.

5. In combination with a block having a groove with over-hanging flanges, a plate-holder, comprising a pair of clamping plates for engaging said flanges, one of said plates having means by which the groove in the block can be cleaned during the act of securing the holder in place.

6. In combination with a block having a groove with over-hanging flanges having beveled edges, a plate-holder having a top-piece for engaging the top of the block, an intermediate piece having beveled edges coöperating with the edges of the flanges, and a base-piece for engaging the bottom of the flanges, and means by which the base-piece may be freely turned in the groove beneath the flanges into operative or inoperative position.

7. A plate-holder comprising a base-piece, a top piece, an intermediate piece the sides of which project beyond the bottom surface of the top-piece, and means for holding the several pieces in coöperative relation, the intermediate piece being arranged midway of the ends of the other pieces and within the planes of the edges of said other pieces.

8. In combination with a block having a groove with overhanging flanges the edges of which are beveled, a plate-holder comprising a top-piece for engaging the top surfaces of the flanges, a base-piece for engaging the bottom surfaces of the flanges, an intermediate piece having beveled edges coöperating with the opposite edges of the flanges, and means for clamping the several pieces in fixed relation to said flanges and wedging the intermediate piece between the latter.

9. A plate-holder comprising a base-piece,

a top-piece, and means for holding the two pieces together, the top-piece having a square lug on its bottom surface arranged centrally of the latter with opposite angles 5 of the lug lying in the longitudinal center of the bottom surface of the top-piece.

10. A plate-holder comprising a base-piece, a top-piece, and a screw for drawing the two pieces into clamping relation, the 15 screw having at one end a washer for co-operation with the bottom surface of the base-piece, whereby the base-piece may be turned in opposite directions by the screw, and means for limiting the turning movement of said base piece.

11. A plate-holder comprising a base-piece, a top-piece, and means for drawing the two pieces together, the top-piece having a beveled edge for co-operation with an edge 20 of the plate, and an angular lug on its bottom surface within the compass of the two pieces, said lug being arranged with opposite sides at an angle to opposite sides of the top-piece, and said lug having a lip 25 for co-operation with the bottom of a plate, said top-piece and lug thus embracing the plate.

12. In combination with a block having a groove therein provided with overhanging

flanges, the edges of which flanges converge 30 from top to bottom, a plate-holder comprising a top-piece, a bottom-piece, a lug located between the two, and means for drawing the several parts together upon the flanges, the top-piece being provided with a beveled edge for co-operation with the plate, the lug being provided with opposite beveled edges 35 co-operating with the flanges of the block, and the base-piece being adapted to enter and turn in the groove of the block.

13. In combination with a block, having a groove with overhanging flanges, a clamp comprising a top-piece, a bottom-piece and an intermediate piece, means for securing the several parts together to clamp the same 40 in operative relation to the block, and means carried on the top surface of one of the pieces for co-operation with the opposite edges of the flanges of the block to limit the movement of the base-piece in opposite directions.

In testimony whereof I have hereunto signed my name in the presence of two subscribing witnesses.

HERMAN TUGENDER.
